UNITED STATES PATENT OFFICE.

FRANK BEYERLE, OF NORTH BRANCH, NEW YORK.

SHANK-LASTING APPARATUS FOR BOOTS AND SHOES.

SPECIFICATION forming part of Letters Patent No. 259,082, dated June 6, 1882.

Application filed February 20, 1882. (No model.)

To all whom it may concern:

Be it known that I, FRANK BEYERLE, of North Branch, in the county of Sullivan and State of New York, have invented a new and 5 Improved Shank-Laster for Boots and Shoes, of which the following is a full, clear, and exact description.

The object of my invention is to facilitate lasting of the shanks of boots and shoes.

10 The invention consists of two clamps adapted to grasp and hold the edges of the shanks, combined with an apertured sliding plate and a screw for pressing the plate through the openings of which the clamps are passed toward 15 the grasping ends of the clamps, whereby the grasping ends of the clamps are moved toward each other and the shanks are tightly stretched on the last.

15 The invention also consists in details of construction, as will be fully described hereinafter.

Reference is to be had to the accompanying drawing, forming a part of this specification, in which a longitudinal perspective view of my improved shank-laster is shown, parts being 25 in section, and the manner of using the implement being shown.

The leather-clamps A are each composed of a fixed jaw-arm, B, and movable jaw-arm C, pivoted on the jaw-arm B, the grasping ends 30 of both jaws being serrated or roughened on the inner surface. The fixed jaw-arm B is extended beyond the pivot, or provided with an elongation, D, which has an angular projection, bend, or flange, E, at the end, and the 35 pivoted jaw-arm C is extended only a short distance beyond the pivot, and this end of the jaw-arm C is provided with a longitudinal slot, through which a curved screw-bolt, F, passes, which screw-bolt passes through the jaw-arm 40 B and is attached to the same. A winged nut, G, is screwed on the outer end of the screw-bolt F. A spiral spring, H, is coiled around the screw-bolt F, and presses the lower end (as shown) of the pivoted jaw-arm C from the jaw-arm B. The grasping ends of the jaws are curved 45 slightly toward that side of the clamp on which the nut G is, and the elongation D of the jaw-arm B is slightly curved from that side of the clamp on which the nut G is, as shown. A 50 plate, J, is provided with two apertures or open-

ings, K, and with a recess, L, in one of the surfaces. The outer edges of the apertures K are beveled outwardly from that surface of the plate J provided with the recess L toward the opposite surface. A screw, M, having one end beveled or rounded, is provided with a transverse handle, N, at the opposite end, and on this screw a nut, O, is loosely mounted—that is, it is screwed on this screw. The end projections or flanges, E, are recessed in their outer 55 edges to adapt these edges to fit closely against the screw.

P represents the last, and Q the leather shanks.

If the recesses of the projections E are screw-threaded, the nut O can be dispensed with; but I prefer the construction shown.

The operation is as follows: The edges of the shanks Q are grasped by means of the clamps A, and are firmly held between the 70 serrated or roughened surfaces of the jaws by screwing the nuts G down tightly. The elongations D of the jaw-arms B are passed through the openings K of the plate J in such a manner that these elongations will be inclined toward each other, the outer surfaces of the elongations resting against the beveled edges of the openings K, as shown. The end of the screw M is placed into the recess L, and the nut O is held against the inner surfaces of the 80 projections E, the recessed edges of which rest against the screw M. The screw is then turned, and thereby presses the plate J in the direction of the arrow a', whereby the grasping ends of the clamps which firmly hold the shanks 85 will be forced toward each other, and the shanks will be stretched tightly on the last P, and can be adjusted in relation to the other parts of the shoe. The shanks can be stretched as much as may be desired by pressing the 90 plate J a greater or less distance in the direction of the arrow a'. If the nuts G are unscrewed, the springs H will separate the jaws, whereby the shanks will be released.

Having thus described my invention, I claim 95 as new and desire to secure by Letters Patent—

1. In a shank-laster, the combination, with the fixed jaws B, of the pivoted jaws C, extended beyond the pivots and having their ends slotted, the screw-bolts F, the nuts G, 100

and the springs H, substantially as and for the purpose set forth.

2. In a shank-laster, the combination, with the clamps A, provided with extensions D, terminating in flanges E at their ends, of the plate J, provided with apertures K, the nut O, and the screw M, substantially as herein shown and described, and for the purpose set forth.

3. In a shank-laster, the combination, with the clamps A, having end projections, E, of the

plate J, provided with apertures K, having their outer edges beveled, and of the screw M, resting on said plate, substantially as herein shown and described, and for the purpose set forth.

FRANK BEYERLE.
